MAXMOOR CORPORATION, OF NEW YORK, N. Y., A CORPORATION OF DELAWARE.

ANTIDETONATING PISTON HEAD FOR INTERNAL-COMBUSTION ENGINES.

Application filed October 13, 1926. Serial No. 141,289.

My invention relates to an anti-detona-
tion piston for four-cycle internal combus-
tion engines, and particularly to a piston
having a head provided with an upward
5 extension adapted to project into the com-
bustion chamber and reduce the available
volume thereof when the piston is at the
upper end of its stroke. The language of the
10 vertical internal combustion engine is em-
ployed herein for convenience of expression,
though not in a limiting sense, as the en-
gine cylinders may be horizontal, or in-
clined, or arranged in other ways.

According to the present invention, the
15 upward extension of the piston head is pref-
erably of substantially helicoidal form, that
is to say, it is highest at the center, and the
remainder of the projection on the piston
20 head is composed of a volute or winding
ramp surface winding downwardly and out-
wardly on a gradual slant from the central
part of the piston head to substantially the
periphery thereof.

The present invention also has for its ob-
25 ject the converting of an internal combustion
engine of any given compression ratio to
one of higher ratio, as, for example, the
changing of an engine of existing low com-
pression to high compression, by attach-
30 ment to the piston head of a crown having a
substantially helicoidal head surface, and
will be best understood from the following
description of an embodiment of the inven-
tion shown in the accompanying drawings,
35 in which Fig. 1 is a sectional view of a valve-
in-head engine having a substantially heli-
coidal piston head. Fig. 2 is an enlarged
plan view of the piston head with the crown
attached. Fig. 3 is a fragmentary part sec-
40 tional view on an enlarged scale. Fig. 4 is
an enlarged detail section of one form of
screw lock. Fig. 5 is a similar view of a
modified form of screw lock. Fig. 6 is a side
view of a piston of somewhat modified for-
45 mation. Fig. 7 is a sectional view and Fig.
8 a plan view of a template for insertion in
a cylinder for drilling the holes in the piston
head. Fig. 9 is a sectional view showing
the use of the template of Fig. 7 for drilling
50 the holes, and Fig. 10 is a detail sectional
view of a modified form of template.

The separate crown 10 has an under sur-
face 12 adapted to fit closely on top of the

head 14 of piston 16. Pistons are usually
constructed with a flat head and in such case 55
the under surface 12 of the crown is flat.

The crown 10 is highest at its center, at
which region it preferably terminates in the
flat nose 18, which may be of a diameter
approximately $\frac{1}{4}$ to $\frac{1}{3}$ of the piston diam- 60
eter. From the nose or platen 18 the volute
ramp surface 20 winds outwardly and down-
wardly to the periphery of crown 10, the
base of which is preferably spaced back from
the margin of the piston, as indicated at 65

The substantially helicoidal crown com-
prising the described portions is adapted to
extend within the combustion chamber when
the piston is at top center position. The
convolutions of the volute slanting ramp sur- 70
face 20 are connected by the substantially
vertical riser surfaces 23, so as to avoid the
presence of any sharp angles or fins. The
number of convolutions of the ramp surface
may be varied substantially as desired, two 75
complete convolutions 20^a and 20^b being
shown in Fig. 2. In the modified form of
crown 10^a shown in Fig. 6, three complete
convolutions 20^m, 20ⁿ and 20^p are shown.
The convolutions of the riser surfaces 23 80
correspond in number with the ramp con-
volutions. In making the crown 10, the nar-
rowest part 24 of the outermost spiral is not
carried down to a thin edge or fin, but is
made of substantial height, as indicated by 85
the dotted line 25, Fig. 3.

It will be apparent that by suitable choice
of the dimensions of the crown 10 substan-
tially any desired change of compression ra- 90
tio can be obtained.

In order to avoid any unnecessary in-
crease in the piston weight the crown 10 is
preferably made of light metal, such as
aluminum. Where considerations of weight
will permit, a higher heat conducting metal, 95
such as copper, may be used.

It is essential that the fastening of the
crown to the piston head be completely close
and secure in order to secure good heat con-
duction and to avoid loosening when the en-
gine is run at high speed, and I have devised
a fastening means which meets these require- 100
ments.

In its preferred form such fastening means
comprises a plurality of machine screws 26 105
with cylindrical heads 28, which are passed

through holes 30 in the crown 10 and screwed into tapped holes 32 in the piston head. The holes 30 are preferably countersunk, as indicated at 34, to receive the screw heads 28, 5 and the depth of the countersunk recesses 34 is preferably the same as the height of the screw heads, so that same are flush with the crown platen surface 10.

When the screws 26 have been screwed 10 home as tight as possible, they are permanently locked in place. The locking means preferably consists of a pin or dowel 36 driven into a hole 38 formed as by drilling partly in the margin of the screw head 28 15 and partly in the material of crown 10.

The dowel or pin 36 after being driven in is permanently secured in place so that it cannot be removed without drilling it out. Two modes of effecting this result are shown. 20 In Figs. 2, 3 and 4 the pin 36, which is beveled off at its upper end, is locked by peening over the material of screw head 38 and crown 10, as indicated at 40, Fig. 4. In Fig. 5 a single screw thread 42 is tapped 25 in the hole 38' and the pin 36', made a little longer than before to provide some extra material, is peened and thereby expanded into the groove 42. Other modes of securing the pin permanently in place may be 30 resorted to, but that shown in Fig. 5 is deemed desirable, as the pin can conveniently be made of material suitable for the required end deformation necessary to secure its permanent fastening into place. So secured, 35 the locking pin is proof against removal or loosening at all engine speeds and conditions, the screw cannot move, and the crown 10 cannot be loosened.

The crowns 10 or 10^a can be made use of 40 in engines of practically any construction, which will permit of increase in compression ratio. In Fig. 1 I have shown the crown or helicoidal portion on the piston 50 of an engine 52 of the valve-in-head type. In this 45 type of engine the combustion chamber 54 is customarily formed partly in the top end of the cylinder 56 and partly in the cylinder head 58 and the crown 10 projects into the combustion chamber and reduces the volume 50 thereof when the piston is at top center, substantially as indicated in Fig. 1. A spark plug 60 is shown in offset relation to and facing the helicoidal portion of the piston 50. This showing is illustrative only, as the 55 crown can be used on heads of substantially any engine piston.

In making a service station application of the crown to the pistons of an automobile engine having a removable cylinder head, a 60 hardened template 60 may be slipped into the cylinder with the guide holes 62 accurately formed therein. The holes 64 are then drilled into the piston head, a stop being 65 preferably used in drilling to gauge the depth of the hole, in order to avoid drilling

through to the other side. In case the holes 62 are to be drilled through, this can be done by removing the crankcase and catching the drillings which fall through. The same template is used in reversed position for drilling the holes 30 in the crown, a flange 66 being provided on the upper side of the template 60 and surrounding a socket or recess 68 therein for receiving and centering the crown, the holes 30 being drilled in the 70 crown through the same guide holes 62 in the template 60.

In case of pistons being removed from the cylinder, as with an engine having a solid cylinder block without the head being made removable, the template 70 of Fig. 10 may be provided, having a guide recess 72 on its under side surrounded by the flange 74. The recess 72 is made just large enough to slip 80 over the piston head and serves to accurately 85 center the holes without resort to the cylinder walls for guiding.

Without being committed to any particular theory, it is my belief that the very considerable increase in compression ratio (of 90 the order of 6:1 or higher) possible to be used with my improved helicoidal crowns without detonation even when the engine is run on ordinary fuel without special anti-detonation components, is due to turbulence 95 created in the combustion chamber by contact of the gases with the crown surface on the intake stroke and by the crown serving to spread and excite the gases on the compression stroke and by a swirling or rotary 100 turbulence due to the helical or screw formation of the outer parts of the crown surface, and furthermore at firing the spiral steps in the crown will serve to break up any pressure wave preceding the travel of flame after 105 ignition. There may also be a surface combustion effect of speeding up the flame travel by gas concentration adjacent to the additional upwardly extending surface area 110 which is supplied by the crown, also a permitting of any pressure wave to expand after passing off the various stages of the ramp surface.

The extra surface area which may be provided by the helicoidal crown formation at 115 the same time that the combustion chamber volume is reduced assists in carrying away any excess heat which could cause detonation or produce areas of local incandescence likely to result in preignition, the turbulence of 120 the gases being effective to secure uniform heat distribution and absence of such incandescent areas.

The highest benefits of the present invention are realized when complete combustion 125 and absence of carbon deposits are obtained by the use of my improved system of combustion, involving the supplying to the engine intake above the throttle of exhaust gas and air at temperatures and in propor- 130

tions and quantities metered to suit the engine requirements at varying speeds and loads, as set forth, for example, in my copending application Serial No. 757,075, filed

5 December 19th, 1924.

The subject matter of my invention disclosed herein and not claimed is disclosed and claimed in part in my copending application Serial No. 140,726, filed October 11, 10 1928, and renewed December 4, 1928, and in part in my copending application Serial No. 142,231, filed October 18, 1926.

This application is also a continuation in part of my copending application Serial No. 15 140,727, filed October 11, 1926.

I claim:

1. A piston for an internal combustion engine, having a separate substantially helicoid crown attached to the head thereof.

20 2. A piston for internal combustion engines, a separate crown on the head of the piston, and means for securing the crown to the piston, comprising screws and locking pins for holding the screws against turning.

25 3. A piston for internal combustion engines, a separate substantially helicoid crown on the head of the piston, screws countersunk flush in the crown and screwed into the piston head, the screwhead and crowns being 30 provided with locking pin holes located partly in each, locking pins in said holes, the metal being peened over the locking pins so as to prevent loosening or removal thereof, except by drilling them out.

35 4. In an internal combustion engine having a cylinder and a combustion chamber therefor, a piston in said cylinder, a separate crown for said piston comprising a plurality of convoluted slanting ramp-like surfaces step related to one another, and permanent locked screw means for securing said crown to the piston head so that said crown will project into the combustion chamber.

40 5. A piston for internal combustion engines, a separate piston head crown having its upper surface comprising a plurality of spirally volute steps, screws for securing said crown to the piston head, and locking pins permanently embedded within the 50 screw and piston head material for permanently holding said screws against turning.

55 6. A piston for internal combustion engines comprising a substantially helicoidal surfaced upward extension including outwardly extending surfaces and vertically extending surfaces connecting the same; the periphery of the upper of said outwardly extending surfaces being disposed inwardly of the inner side of the outwardly extending 60 surface below the same.

65 7. A piston for internal combustion engines comprising an extension of substantially step formation on the head thereof having transversely extending step surfaces and vertically extending riser surfaces there-

between; said extension tapering towards the top thereof, and said transverse surfaces consisting of spiral convolutions decreasing in height and increasing in magnitude towards the base thereof.

70

8. A piston for internal combustion engines comprising a tapering extension thereon of substantially step formation having transversely extending step surfaces and vertically extending riser surfaces therebetween of less height than the width of said transverse surfaces; said transverse and vertically extending surfaces consisting of spiral convolutions decreasing in height and increasing in magnitude towards the base 80 thereof.

75

9. A piston for internal combustion engines comprising an extension thereon of substantially step formation decreasing in cross-sectional area towards the top thereof, 85 and having a substantially large base compared to the height of the extension; the transverse step surfaces thereof consisting of spiral convolutions decreasing in height and increasing in magnitude towards the base 90 thereof, and the riser surfaces thereof being disposed substantially vertical.

10. A piston for internal combustion engines comprising an extension thereon of substantially step formation decreasing in 95 cross-sectional area towards the top thereof; the transverse step surfaces thereof consisting of spiral convolutions, and the riser surfaces thereof connecting the same forming therewith angles each at least substantially 100 as great as a right angle.

11. A piston for internal combustion engines comprising an upward extension thereon of substantially step formation decreasing in cross-sectional area towards the top 105 thereof, and having a substantially flat central portion, and transverse step surfaces consisting of spiral convolutions surrounding said central portion and extending downwardly therefrom and outwardly towards the periphery of the piston.

110 12. A piston for internal combustion engines comprising an extension thereon of substantially step formation decreasing in cross-sectional area towards the top thereof, 115 and terminating in a substantially flat horizontal surface; the transverse step surfaces of the extension consisting of spiral convolutions surrounding said flat horizontal surface and extending downwardly therefrom and outwardly towards the periphery of the piston.

120 13. A piston for internal combustion engines comprising an extension thereon of substantially step formation decreasing in 125 cross-sectional area towards the top thereof and terminating in a substantially flat horizontal central surface; the transverse step surfaces of the extension consisting of spiral convolutions disposed about said central sur- 130

face and decreasing in height and increasing in size towards the base thereof, and the riser surfaces thereof being disposed substantially vertically and having a height less than the width of said transverse step surfaces and forming substantially right angles therewith.

14. An internal combustion engine comprising a cylinder, and a piston therein having a head of step formation increasing in height from the periphery thereof towards the center thereof, and ignition means in said combustion chamber disposed in offset relation to said piston in the top center posi-

tion thereof and facing the riser surfaces of 15 said step formation.

15. An internal combustion engine comprising a cylinder, and a piston therein having a head of helicoidal step formation increasing in height from the periphery thereof towards the center thereof, and ignition means in said combustion chamber disposed in offset relation to said piston in the top center position thereof and facing the riser surfaces of said step formation.
